UNITED STATES PATENT OFFICE.

FREDERICK T. ACKLAND, HENRY G. MITCHELL, AND MUSTAPHA MUSTAPHA,
OF ZAGAZIG, EGYPT.

IMPROVEMENT IN COTTON-GINS.

Specification forming part of Letters Patent No. 58,187, dated September 18, 1866.

To all whom it may concern:

Be it known that we, FREDERICK TABOR ACKLAND, HENRY GEORGE MITCHELL, and MUSTAPHA MUSTAPHA, of Zagazig, Egypt, have invented certain new and useful Improvements in Cotton-Gins; and we hereby declare the following to be a full, clear, and exact description of the same, reference being had to the accompanying drawings.

The said invention relates to a peculiar construction and arrangement of self-acting mechanism for feeding cotton-gins, whereby a more regular and certain feed is obtained than by the mechanism heretofore adopted for that purpose.

According to this invention it is proposed to apply to the ordinary McCarthy gin, or to other gins of a like character, a self-acting feeder, which reciprocates to and fro in a rectilinear or straight course, and imparts a direct push to the cotton, so as to move it forward by a positive motion to the ginning-roller and "doctor" as fast as it is fed into the feeding-hopper.

This feeder consists of a bar of wood, metal, wire-work, or other suitable material, of a length equal to that of the ginning-roller, which bar is situate inside the hopper parallel to the axis of the said roller. This feeding-bar reciprocates toward and from the ginning-roller and its doctor along the grid upon which it rests, its motion being derived directly from cranks or eccentrics on a shaft contained within the back portion of the hopper. As fast as the cotton is supplied to the hopper it falls at each back stroke of the feeder in front of the forward edge or face thereof, so that when the feeder returns toward the ginning-roller and doctor it pushes that portion of the cotton immediately in front of it directly against the said roller and doctor and then recedes for a fresh supply, which is again pushed forward as before, and so on; and in order that the said invention may be fully understood we shall now proceed more particularly to describe the same, and for that purpose we shall refer to the figures on the sheet of drawings hereunto annexed, the same letters of reference indicating corresponding parts in both of the figures.

Figure 1 of the drawings represents a side elevation of an improved McCarthy gin pro-

vided with the above-described self-acting feeder; and Fig. 2 is a vertical section of the upper part of the gin on a larger scale, showing more clearly the construction and operation of the feeder.

A represents one of the two side standards of the gin. B is the main driving-shaft, and C is the shaft of the ordinary leather-covered ginning-roller D. E is the doctor or fixed knife. F is the vibrating beater-plate, attached to the radius-rod G, which works on a fixed center at H, and derives its motion from a crank on the main shaft and a connecting-rod, I. K is a feeding-hopper, and L the grating or grid, all which parts are common to gins of this class, and form no part of the present invention, which has reference solely to the feeding mechanism, hereinafter more particularly described or referred to.

M is the reciprocating feeder. It extends from end to end of the hopper, within which it is contained, is parallel to the surface of the ginning-roller D, and slides toward and from such roller along the grating or grid L. A rectilinear reciprocating motion is imparted to the feeder M by means of a crank-shaft, N, revolving in adjustable bearings O in the ends of the hopper.

P represents one of two connecting-rods, which connect the feeding-bar M with its actuating-cranks on the crank-shaft N. A pulley, Q, is keyed onto one end of the crank-shaft N, and a corresponding pulley of equal diameter, R, is keyed onto one end of the main driving-shaft, motion being transmitted from such pulley to the crank-shaft by the band S.

The cotton to be fed into the machine is laid upon the table T, and is thence pushed by hand down the inclined side of the hopper, to the lower edge of which a flap, U, of leather or other suitable material is secured, for the purpose of preventing any of the cotton from entering behind the feeder. As the feeder advances its front edge or face, m, pushes the cotton before it against the ginning-roller and doctor, which seize it and remove the seeds therefrom in the well-known manner.

Having now described and particularly ascertained the nature of the said invention and in what manner the same is or may be used or carried into effect, we would observe in con-

clusion that what we claim as novel and original, and as forming the essential feature of our invention, is—

The application and use to and in the McCarthy cotton-gin, or other cotton-gins of a like character, of a feeding bar or surface having a rectilinear reciprocating motion along the grid or grating, for the purpose of pushing the cotton up to the ginning-roller and doctor, substantially as hereinbefore described, and illustrated by the annexed sheet of drawings.

In testimony whereof we have signed our names to this specification in the presence of two subscribing witnesses.

FREDERICK TABOR ACKLAND.
HENRY GEORGE MITCHELL,
By F. T. ACKLAND.
MUSTAPHA MUSTAPHA.
